UNITED STATES PATENT OFFICE.

JOHN W. ARNOLD, OF SAN FRANCISCO, CALIFORNIA.

LUBRICATOR FOR FLUID-ACTUATED APPARATUS.

Application filed October 12, 1925. Serial No. 62,168.

To all whom it may concern:

Be it known that I, JOHN W. ARNOLD, a citizen of the United States, and a resident of San Francisco, in the county of San Francisco and State of California, have invented a new and useful Improvement in Lubricators for Fluid-Actuated Apparatus, of which the following is a specification.

This invention relates to lubricators for fluid actuated devices, such as hammers, drills and the like.

The general object of the invention is the provision of a simple and efficient lubricator adapted to supply lubricant not possible to be entrained by compressed fluid entering the fluid actuated device, and further adapted to permit of replenishing the supply of lubricant during the operation of the fluid actuated device.

20 The above and other objects are accomplished by instrumentalities pointed out in the following specification.

The invention is clearly defined in the claims.

25 A satisfactory embodiment of the invention is illustrated in the accompanying drawings forming part of the specification and in which—

Figure 1 is a side elevation of the device 30 in use.

Figure 2 is a detail vertical longitudinal section of the device.

Figure 3 is a central cross section looking at right angles to Figure 2, and

35 Figure 4 is a detail perspective of the blow-back valve.

In the drawings 5 indicates the hammer, 6 the handle, 7 the lever for actuating the control valve, 8 the flexible connection for supplying compressed fluid to the hammer and the flow of which is controlled by the valve operable by the lever 7. These parts are all of well known construction. The lubricator forming the subject matter of the 40 present invention is designated generally by *a* and is herein shown as forming the means for connecting the flexible connection to the handle 6. In the embodiment shown the lubricator comprises a hollow casing 9 of cylindrical contour having at one end a female fitting 10 which is screwed upon the end of handle 6, and its opposite end is provided with a male fitting 11 which is connected by a union 12 to the flexible connection 8. An open-ended tubular container 13 screwed into an open-ended transverse pas-

sage 14 in casing 9 is adapted for holding the lubricant, such as oil to be supplied to the fluid actuated device, such as the hammer 5. A chamber 15 is formed within the container 13 by means of plates 16 and 17 screwed into one end of the container and spaced apart therein, as shown. The chamber 15 in turn communicates with the longitudinal passage 18 of the casing through a plurality of ports 19 formed in the walls of the chamber, as shown. The inlet end of the container which is the end thereof remote from the chamber 15 has a valve seat 20 screwed therein, and the passage 21 of the seat 20 constitutes the fluid inlet or filling passage for the container 13. The passage 21 has an inwardly flared or tapered portion which accommodates a correspondingly shaped portion of an inlet control valve 22, and a shank 23 extending inwardly from the base of the inlet valve 22 terminates in a needle point 24 adapted to enter a needle valve 25 in the inner disk 16 and thereby control the outlet from the container 13 or communication between the said container and the chamber 15. A helical compression spring 25' is disposed within the container and surrounds the shank 23 and constantly urges the inlet valve 22 to close the inlet passage 21. The inlet valve 22 and the length of the shank 23 are such that when the inlet valve closes the inlet passage, the needle point 24 will open the passage between the container and the chamber 15. When the 50 inlet valve is operated to open the inlet opening 21 and moves inwardly and away from the tapered surface, the needle point 24 closes the passage between the container and the chamber. The inlet valve 22 is provided with an extension 26 extending outwardly from the flared portion thereof, and extending inwardly from the extension 26 is a passage 27, the inner end of which communicates with an axial duct 28 that in turn communicates with one or more laterally extending ducts 29 opening through the side of the inlet valve 22. It will be noted that by reference to Figure 2 that when the inlet valve is in open position, communication between the interior of the container and the exterior is effected through the ducts 29, 28 and the passage 27.

The passage 27, however, is valve controlled by the presence of a blow-back valve 30 which is retained against outward displacement from the passage 27 by an annu-

- 20
- lar valve seat 31 screwed into the outer end of the passage. The blow-back valve shown in Figure 4 is provided with peripheral passages 32 located between radial arms 33.
- 5 The body of the valve 30 is of a size to cover the seat 31 when its valve is in its normal closed position under the action of a helical compression spring 34. When the parts are so positioned as shown in Figures 2 and 3, 10 the blow-back valve may be forced inwardly by the spout of an oil can inserted into the passage 30', whereupon oil directed against the blow-back valve will flow through the passages 32, the ducts 29 and finally into the container 13. A plurality of oppositely disposed cylindrical tubes 35 are 15 screwed into the container 13. The outer ends of these tubes are closed and the tubes by their presence increase the capacity of 20 the container.

In the drawings I have shown a manually operable means for mechanically operating the valve 22, the said means comprising a cylindrical housing 36 having at one 25 end a head 37 which is provided with a central opening for the reception of the male fitting 11, the head also bearing on one end of the casing 9 and the fitting supporting one end of the housing. An annular head 30 38 is screwed into the opposite end of the housing and surrounds the female fitting 10. An annular space 39 is provided between the housing 36 and casing 9, and a cam 40 secured to the housing is disposed 35 within the space 39, and an inlet opening 41 extends through the said wall of the housing and through the wider end portion of the cam. The housing is operable upon the fittings 10 and 11 for the purpose of moving the opening 41 into and out of alignment with the passage 27. When the opening 41 and passage 27 are in alignment, the thickened end of the cam bears upon the inlet valve 22, and the said valve is forced 40 inwardly against the action of spring 25, so that needle point 24 closes the passage between the container and the chamber 15. This is the position of the parts when 45 replenishing the supply of lubricant within 50 the container 13.

When the housing is turned in a counter-clockwise direction from the position shown in Figure 3, the solid part of the housing moves over the passage 27 and, at the same 55 time, inlet valve 22 moves outwardly under the action of its spring and due to the slope of the inner face of the cam 40.

With this construction it is obvious that 60 the operation of replenishing the supply of lubricant within the container may be carried out without cutting off the supply of fluid to the fluid operated device. If so desired, stops 42 and 43 may be provided, as 65 shown in Figure 3, on the opposite faces of the housing and casing to limit the move-

ment of the housing in one direction when the opening 41 thereof registers with the passage 27.

Although I have shown and described one embodiment of my invention, it is to be understood that the same is susceptible of various changes; and I reserve the right to employ such as may come within the scope of the appended claims.

I claim:

1. A lubricator comprising a casing, a fluid connection leading into the casing, a container having a chamber communicating therewith for delivering oil in position to be entrained by fluid supplied by the connection and an inlet passage through which lubricant is supplied to the container, a valve member disposed within the container having opposite end portions adapted for controlling communication between the container and chamber and passage through the inlet opening, said valve member being bodily movable in one direction to cut off communication between the container and chamber and to open the inlet passage.

2. A lubricator comprising a casing, a fluid connection leading into the casing, a container having a chamber communicating therewith for delivering oil in position to be entrained by fluid supplied by the connection and an inlet passage through which lubricant is supplied to the container, a valve member disposed within the container having opposite end portions adapted for controlling communication between the container and chamber and passage through the inlet opening, said valve member being bodily movable in one direction to cut off communication between the container and chamber and to open the inlet passage, and also movable bodily in an opposite direction to effect communication between the chamber and container and to close the inlet passage.

3. A lubricator comprising a casing, a fluid connection leading into the casing, a container within the casing having a compartment for delivering lubricant in position to be entrained by fluid supplied by the connection, said container having oppositely disposed openings, one of which provides an inlet passage and the other an outlet leading to the chamber, a movable valve member disposed within the container having one end portion normally closing the inlet passage and its opposite end portion disposed in spaced relation to the outlet opening, and manually operable means for moving the valve member to simultaneously open the inlet passage and close the outlet passage.

4. A lubricator comprising a casing, a fluid connection leading into the casing, a container within the casing having a compartment for delivering lubricant in position to be entrained by fluid supplied by

the connection, said container having oppositely disposed openings, one of which provides an inlet passage and the other an outlet leading to the chamber, a movable valve member disposed within the container, a spring operating to hold said valve member so that one end thereof normally closes the inlet passage and the opposite end uncovers the outlet passage, and manually operable means for moving said valve member against the action of said spring to simultaneously open the inlet passage and close the outlet passage.

5. A lubricator comprising a casing, a fluid connection leading into the casing, a container within the casing having a compartment for delivering lubricant in position to be entrained by fluid supplied by

the connection, said container having oppositely disposed openings, one of which provides an inlet passage and the other an outlet leading to the chamber, a movable valve member disposed within the container having one end portion normally closing the inlet passage and provided with a valve controlled inlet duct leading into the inlet passage, the opposite end portion of said valve member being disposed in spaced relation to the outlet opening, and a manually operable means adapted to be moved in opposite directions to expose and close said duct, and further adapted to move the valve member to simultaneously open the inlet passage and close the outlet passage.

JOHN W. ARNOLD.
